UNITED STATES PATENT OFFICE.

SAMUEL P. BUSH, OF COLUMBUS, OHIO, ASSIGNOR TO THE BUCKEYE STEEL CASTINGS COMPANY, OF COLUMBUS, OHIO.

SPRING SUPPORT.

Original application filed September 28, 1925, Serial No. 59,168. Divided and this application filed May 29, 1926. Serial No. 112,577.

This application is a division of an application filed by me September 28th, 1925, Serial No. 59,168, the object of the present invention being to provide a construction which will permit the side frame to be removed as a unit without materially disturbing the spring plank, springs and bolster in relation to each other, thereby reducing the cost of changing wheels as well as the period during which the equipment is out of service. The invention is illustrated in the accompanying drawings and consists in certain novel features which will be hereinafter first fully described and then more particularly pointed out in the appended claims.

In the drawings—

Figure 1 is a side view of a portion of a car truck embodying the invention.

Figure 2 is a plan view of the same,

Figure 3 is a central transverse section,

Figure 4 is a detail of a key or removable stop lug.

The side frame 1 is shown with integral journal boxes 2, although the journal boxes need not be integral. The side frame has vertical columns which define a central opening 3 to receive the end of the bolster 4 and the springs 5 upon which the bolster end rests. In the bottom 6 of the side frame is a pocket 7, and the end of the spring plank 8 is turned down, as at 9, to fit snugly in the pocket, the plank, of course, extending between and connecting the two side frames of the truck. The springs rest upon a spring seat 10 which extends through the lower portion of the opening 3 and over the pocket 7 with one end fitting between the side flanges 11 of the spring plank, the spring seat being formed with side flanges 12 to attain rigidity and strength. The flanges 11 terminate at the side frame and fit closely between the lugs or flanges 13 thereon, the interfitting engagement of the several flanges minimizing the effects of the stress on the bend of the spring plank.

The weight of the springs is carried by the spring seat which, extending over the end of the spring plank, holds the plank firmly in place. As a loaded car sways from side to side over uneven track, there is an unequal distribution of pressure upon the opposite ends of the group of springs when the bolster is tilted under a heavy side bearing load or blow. The drawings show means

for overcoming this inequality consisting of a rib or rocker 14 on the under side of the spring seat fitting in the pocket 7 and provided in its lower face with a transverse concavity 15 resting on a convex saddle 16 in the pocket, the saddle constituting a fulcrum or pivotal support about which the angularity of the bolster will freely accommodate itself.

At the top of the central opening 3 in the side frame, in the sides thereof, are grooves or reentrant recesses 17 which permit the frame to be passed over the end of the bolster, the projections 18 on the bolster passing through said recesses or grooves and the bolster being then lowered to rest on the springs. The movement of the frame over the bolster is arrested by contact with the lugs 19 on the sides of the bolster which are preferably cast integral therewith. Under normal conditions of operating, the side frames restrict the transverse movements of the bolster by contact with the inside stops 19 or the outside stops 20 arranged in spaced relation at each side of the bolster. The outside stops 20 are constructed as separate parts and are held in a definitely spaced relation to the inside stops through direct interlocking with the bolster, preferably without the use of any third part, such as a bolt or rivet, for maintaining the relation.

The outside stop is shown as a U-shaped key adapted to fit with its cross bar in the groove 21 in the underside of the bolster and with its side arms between the side frame and the lugs 18 on the bolster. The keys are between the bolster and the springs and are held in place primarily by the weight or load carried by the bolster and springs. Heretofore, the opening 3 in the frame has been wider in its lower portion than in its upper portion to permit it to pass over the outside column lugs of the bolster which construction required a relatively longer spring seat member on the frame. The relatively shorter length permitted by the construction herein set forth adds materially to the strength of the device.

In car trucks of the usual construction, the bolster stops were generally not intended to be removed for the convenience of dismantling the trucks, but were either cast integral with the bolster or secured to the same through permanent mechanical means.

To facilitate assembling or disassembling of the trucks, the bolster opening was provided with an enlargement through which the outside bolster guides were free to pass after 5 the side frame and bolster were brought into proper alinement and height relation with respect to each other by raising the side frame or lowering the bolster. In trucks having the journal boxes integral with the 10 side frame, it necessitated the removal of springs, spring plank, and certain brake parts to bring the bolster into proper relation to the enlarged portion of the bolster opening before the side frame could be withdrawn.

With my improved construction, the grooves or recesses 17 at the top of the bolster opening 3 permit the frame to be passed over the end of the bolster, the projections 18 on the bolster passing through said grooves or recesses. The bolster is first slightly and easily lifted from the springs to release the keys or stops 20 and permit them to be withdrawn. After withdrawing 25 the stops or keys, the bolster is again lowered to rest on the springs, whereupon the spring plank, with the superposed springs and bolster, is raised sufficiently to clear the interlocking engagement between the spring 30 plank and the side frame. The side frame may then be moved sidewise away from the truck without materially disturbing the spring plank, springs, or bolster, thereby reducing the cost of replacing wheels or frames 35 and expediting the work.

Having fully described my invention what I claim as new and desire to secure by Letters-Patent, is:—

1. In a car truck, the combination of a side frame having an opening therethrough 40 to receive a bolster and provided with a transverse groove in the wall of said opening near the upper end thereof, a group of springs carried by the side frame in the lower end of the opening, a bolster having 45 its end supported within the opening by the springs, the bolster being provided with a transverse channel in its bottom and with inner and outer lugs on its side, the outer lug being arranged to pass through the 50 transverse groove and the inner lug to abut the inner side of the side frame, and a single U-shaped key engaging snugly between the outer side of the side frame and the outer lug on the bolster and in the channel in the 55 bottom of the bolster.

2. In a car truck, the combination of a side frame, a bolster engaged through the side frame and provided with spaced lugs on its sides, the inner lugs abutting the side frame, 60 a group of springs supported in the side frame and supporting the bolster, and a U-shaped key passing across the bottom of the bolster and held thereto by the springs and having side portions fitting between the side 65 frames and the outer lugs on the bolster.

In testimony whereof, I have signed this specification.

SAMUEL P. BUSH.
